UNITED STATES PATENT OFFICE.

WALTER J. ENNISON, OF BROOKLYN, NEW YORK.

GAME-BOARD.

1,155,714.

Specification of Letters Patent.

Patented Oct. 5, 1915.

Application filed May 17, 1907. Serial No. 374,257.

To all whom it may concern:

Be it known that I, WALTER J. ENNISON, a citizen of the United States, residing at Brooklyn, county of Kings, and State of New York, have invented certain new and useful Improvements in Game-Boards, fully described and represented in the following specification and the accompanying drawings, forming a part of the same.

10 My invention relates to game-boards and more particularly that class simulating baseball.

My object is to provide a game controlled somewhat by chance, but largely admitting 15 of the exercise of one's knowledge and skill as practised in the well known game of baseball under league rules. In the attainment of this end I employ a game-board on which is represented a baseball field with counters 20 for players thereon, to which I add features consisting of figures characterizing certain portions of each of the various fields, a movable piece representative of a ball, designations for the path of the ball, and an indicator device by means of which the movements 25 of the ball-piece about the board are determined in a manner similar to the flights of the ball in the out-of-door game, and the elements of chance are in a measure sub- 30 ordinated to the skill of the players and the contest, as it may be called, between the man and the ball, supplies the chief interest alike of the game presented, and that represented thereby.

35 For a more detailed description of my invention, reference is had to the following described drawings, which are made part of this specification, in which my new game is shown in its most complete form, embodying 40 all the various features of the invention.

In the drawings: Figure 1 is a plan view 45 of the game-board; Fig. 2, partial section of board on line 2—2 in Fig. 1, showing indicator device in elevation; Fig. 3, plan of indicator device; Figs. 4, 5 and 6 are broken portions of the plan view.

The reference letter A (Fig. 1) designates the game-board upon which is a diagram of a baseball field comprising a "diamond" 50 having sides b ; and at the four corners thereof, base-plates b^1 , b^2 , b^3 and b^4 representing respectively 1st base, 2nd base, 3rd base and the home-plate, in the usual order of arrangement. Along each of the sides b 55 of the diamond at equal intervals are miniature diamonds c dividing the runways be-

tween bases into four steps, numbered consecutively, beginning at each base and counting the next following base as the fourth step thereof, which are employed to mark 60 the progress of base-runners as they move about the diamond in their efforts to complete the "home-run" and secure a point for their respective sides.

On the board A are shown two sets of 65 counters a and a^1 , representing respectively the players of the two opposing teams in positions they might assume during the progress of a game.

Modifying the conventional base-ball diagram I have given each of the fielders or out-players, excepting the pitcher, a group or cycle of numbered positions d , which are arranged in similar series about the respective players to which they are assigned. As 70 will be more fully explained in another connection, these designated positions, which in the preferred forms of my invention are uniformly six in number, provide a convenient means for determining the location 75 to which the ball may be thrown or batted, and at the same time serve as graduated runways to be utilized, under the rules of the game with the aid of an indicator device, to be more fully described hereinafter, 80 in defining various plays such as catching, muffing, or recovering the ball which has not been caught, or carrying it to the base when required.

Of the numbered stands which are devoted 90 to the bases it will be observed that those with the numerals 4, 5 and 6, at first and second bases, b^1 , b^2 ; those with the numerals 1, 2 and 3, at third base b^3 ; and those with the numerals 2, 4 and 5, at the home-plate, b^4 , are shown with the circles containing 95 those particular numerals partially resting upon the base plates to which they are related. It is thus provided that when a man is standing upon one of these numbered circles which actually contacts the base in the manner described, he may be said to be standing "on his base;" or when 100 "standing" upon a numbered position not thus touching the base, he would be considered as "off his base."

The numbered positions at the home-plate, b^4 , it has been seen, are arranged in a manner differing from the other base plates, having been designed to perform a 110 further function, namely, that of marking imaginary paths of the ball thrown by the

pitcher to the batter or catcher as showing their relation to the home-plate, whether passing directly over the plate or to either side thereof.

5 To represent graphically the paths of balls pitched in the manner described, I have shown a plurality of dotted lines, f^2 , extending from the pitcher's box, e , to the catcher's circle f , each of which passes through a 10 numbered position f^1 at the home-plate. As in the out-doors game balls are thrown to afford the man at the bat an opportunity to hit the same, so in the present game the numbered circles at the plate are intended to 15 supply a similar feature. For this purpose any one of the numbered positions may be used as an imaginary, that is, a temporary resting place for the ball, supposed to be in transit along the dotted line leading to 20 such circle, until it may be determined by indicating means, to be hereinafter explained, if it shall be hit or missed by the batter. If not hit by the batter the ball of course should pass on from its temporary 25 place to the same number in the catcher's circle; and as a matter of fact the plan of my apparatus contemplates that the ball be considered as having gone directly to the indicated number in the catcher's circle, when 30 such should be the case, notwithstanding its temporary stoppage at the home-plate as described. It should therefore be considered that a ball passing along the dotted line cutting the circle at the left of the home-plate 35 bearing the numeral 6 or that at the right having the numeral 3 may, according to the generally recognized rules of baseball, constitute a "called" ball, as in neither instance could the ball be said to have passed "over 40 the plate." In a like manner, a ball passing from the pitcher to the catcher along the dotted line cutting circle No. 1 which circle is not touching the home-plate while its 45 path does, may by a slight stretching of the analogy be considered technically as not properly over the home-plate, conforming in that particular to a ball which is said to be "too high" or "too low," although passing over the plate as shown, and which also 50 counts as a "called" ball against the pitcher's team.

The pitcher's box e (Fig. 1) is divided into four parts, the first of which is marked with the letter P , and the remaining three 55 with the numerals 1, 2 and 3, next following P in the order named, to be employed in recording "called" balls, the pitcher piece normally standing on the square marked P and moving one square for each "called" 60 ball.

The movable piece g (Fig. 1) representing the ball, is required in order to play the game according to the rules of baseball as contemplated by my invention, which 65 ball-piece may be directed to move about the

board in accordance with the readings of any suitable indicating device, such as ordinary dice, specially prepared cards, or any simple spinning indicator with numbers or characters corresponding to those of the designated positions of the fielders on the board. But in my preferred construction of the apparatus I have a two-fold indicator h (Figs. 1, 3 and 5), which is composed of a dial h^1 conveniently placed upon the board 70 75 A as shown (Figs. 1, 2 and 3) having a fixed pointed radial arrow j and, within the circle of the dial, a rotatable disk i secured to vertical shaft i^1 having a bearing point i^2 and an independently revoluble pointer j^1 80 85 loosely mounted upon the said shaft.

The dial h^1 is divided by radial lines into segments of varying lengths proportioned approximately to the chances as they occur in the game of baseball, within some of 90 which segments are inscribed the names by which the out-players are designated, and in each of the remaining segments is repeated the word "strike," of which there are eight 95 in number, shown by arbitrary arrangement 100 alternating with the segments containing the names of players.

The rotatable disk i is secured to the vertical shaft i^1 by means of the bend i^4 therein (Figs. 2 and 3) with the thumb piece i^2 in the form of a miniature baseball also secured to the shaft i^1 , and is adapted to rotate within the dial h^1 as has been seen. The face of the disk i is divided equally by radial lines into six primary sections d^2 , 105 within which are series of six numbers d^1 inclosed in small circles and symmetrically arranged in somewhat similar manner to that of the numbered positions d upon the game-board to which they relate in the operation of the game. The primary sections d^2 are sub-divided each into two or more segmental panels c^2 , located upon the rim of the disk, and forming a continuous circle, but separated by radial lines and contains a second series of numerals c^1 , one or 110 more of which are inclosed within each of the panels c^2 , which numerals c^1 , it will be shown are employed to regulate and define the movements on the board of the men of 115 both teams.

The indicator device comprises two indexes, one the revoluble pointer j^1 , which has been made in the form of a miniature ball-bat and may be termed the "bat-index," 120 (to be used for the purposes of in-players), and the other, which may be called the "ball-index," (to be devoted to the uses of the out-players) which is in the form of an arrow extending from the representation of a base-ball radially through a section of the dial h^1 , and whose point is in close proximity to the periphery of the rotatable disk i . It will therefore be seen that 125 when the rotating disk comes to a stop the 130

ball-index j will point to one of the primary sections d^2 of the disk which will accordingly indicate that the ball must be placed upon the board at that numbered position d , of the fielder to whom it is desired to throw it, which corresponds to the number d^1 in the primary section to which the arrow j points, and at the same time it will be observed that the ball-index points to one of the sub-sections c^2 , on the rim of the disk which indicates that the fielder to whom it is thrown in order to reach the ball when not caught, or a baseman to carry the ball to the base when it has been recovered, may move as many steps in either direction about his runway as there are units in the selected number c^1 , in the sub-section c^2 , to which the index points. In like manner these same indicated numerals c^1 of the ball index are employed to advance the fielder between bases in pursuit of the runner as many stages as there are units in the number or numbers of the index as selected. It will be noted in this connection that the value of these index numbers c^1 for any one setting of the indicator depends wholly upon the numbered position occupied by the fielder (to whom a ball has been thrown or batted) with relation to the particular spot or number that contains the ball.

The circle described by the point of the bat-index j^1 has been designed to fall within that on which are arranged the numerals c^2 and also the numerals d^2 upon the disk i , hence it is apparent that when this index comes to a stop it will point to a number or numbers of the same two series as does the ball index j , as above described, but from an opposite direction, pointing outwardly. The range of the bat-index however extends beyond the numbers on the disk i , to the segments of the outer dial h , thereby determining the result of the "batting." That is to say, if the bat-index points to a panel of the dial containing the word "strike," it indicates that the ball has not been hit by the batter who has therefore made a "strike." But on the other hand, if the bat-index points to a panel relating to a player, it shows that the ball has been batted to the fielder designated thereby, and taking, in conjunction therewith, the numbers in the section and sub-section of the disk to which the bat indicator also points, it is determined to what numbered position d of such fielder the ball has been batted in accordance with the number d^1 selected, and in addition, by means of the number or choice of numbers c^1 of the same index, it is further determined what number of stages or steps the batter (who then becomes a runner) advances toward his base or bases, he moving one numbered step of the runway about the diamond for each unit of the number c^1 selected.

Back of the catcher's stand, f , (Fig. 1) a rectangular figure is shown, containing the letter U, to which are appended two similar squares having numerals 1 and 2 in the order named. At the beginning of the batting play the umpire piece a^3 stands normally upon the square marked U but is placed upon square marked No. 1 to record the first "called strike" that has been decided in the manner described, to be placed upon the square marked 2 to count the second strike; and back to his original position upon the square "U" on the third strike being called, as the man has thereby been "put out," and a new man "goes to the bat."

I omit as unnecessary a recital of the general rules of the game of baseball under which my game apparatus is designed to be played, deeming it essential to specify only those plays which it is the especial purpose of my invention to supply, pointing out the connection which such plays, as herein described, sustain toward similar features of the outdoors game; thus are deduced the directions or special rules governing the present game.

The ball may be thrown to any part of the field to whichever player desired by the person representing the outplayers, by spinning the disk and placing the ball upon the numbered position d of such player corresponding to the number d^1 of the disk i to which the ball-index j points. For example, the ball-index j in Fig. 1 is pointing to the primary section d^2 of the disk containing numeral 5, of the fielder to whom it is desired to throw the ball; the ball g being shown in Fig. 1 at numbered position 5 of the home plate, showing that the ball was thrown by the pitcher to the catcher to give the batter an opportunity to strike at it. In Fig. 3 likewise, the ball index points to the section of the disk containing the numeral 3 and thereby "throws" the ball to #3 position of the player selected as is shown in Fig. 4, which figure is also illustrative of a ball having been "thrown" to the batter.

A ball is batted by spinning the bat index j^1 and carrying the ball to the player to which the index points upon coming to a stop, placing it upon the numbered position corresponding to the numbered section of the disk also selected by the bat index in the manner hereinbefore described, for example: The bat index j^1 (Fig. 1) is shown pointing to a segment of the dial marked, "Center field," and also to the primary section of the disk i containing the numeral 2 which indicates that the ball has been batted to the center field to position 2 shown in Fig. 1.

To catch a "fly" ball.—When the fielder, to whom it has been batted in the manner last above described, is standing upon that

numbered position to which the ball has been driven, he is said to catch the ball "on the fly," for example: In Fig. 1 the man a^1 in the right field is shown standing upon position No. 6, and in Fig. 3 the bat index shows the ball to have been batted in the manner described to the right field to the numbered position upon which that fielder is standing.

- 10 To catch a ball (not a "fly" ball) or to recover one that has not been caught, the sub-section c^2 of the ball-index contains a number whose units will carry the man from the circle upon which he stands in either direction to that to which the ball has been thrown or batted as described, and in similar manner.

A ball is "muffed" or "fumbled" when the sub-section c^2 of the ball-index does not contain a numeral whose units would exactly carry the fielder to the numbered position to which it has been thrown or batted. For example: The bat-index shows the ball to have been batted to center field to position No. 2 (in Fig. 1) and the ball g is accordingly shown in dotted line in the position indicated but it will be seen that the sub-section c^2 of the disk to which the bat-index points contains the numerals 1 and 3, of which the latter in this instance determines that the ball, (but not a "fly") has been caught or recovered, because the man a^1 in center field stands upon circle No. 5, which is removed three steps in his runway from the ball. However, had the ball fallen in center field, on position No. 1, or No. 3 either of which positions is just two stages from the ball, it would have been in such case "muffed", that is, the player would have failed to recover the ball, because the index square c^2 of the disk does not supply a numeral with the two units that would be required in the case supposed.

In a similar manner a runner or baseman with the ball "reaches his base," and similarly a baseman overtakes a runner between bases when the sub-section c^2 of the disk to which his index points contains a number c whose units exactly carry the man from his initial position to his objective in the manner described.

Operation.—I will now illustrate the manner of operating my apparatus by describing the various plays which may compose one-half of an inning of the game of baseball, in the order of their occurrence. The men a^1 representing the outplayers, take their respective places as shown in Fig. 1, while the men at the bat are arranged in batting order at some convenient place near the diamond. On the board A I have shown the third batter in position at the bat, having assumed that two batters have preceded him, one having reached third base b^3 , while the other is safe on first base b^1 as

shown. I therefore assume that batter No. 3 takes his position in one of the rectangles R or L (which are approximately the positions taken by batters on the field, according to whether right or left handed). The person representing the out-players spins the disk i and the ball-index j points to that section d of the disk i containing the numeral 5, and in accordance therewith places the ball as shown upon No. 5 at the home-plate. This means that the pitcher threw the ball along the imaginary line that passes through circle No. 5, which is directly over the plate. Hence, the ball having been properly delivered, the batter strikes at it by spinning the bat-index j^1 , which points to three readings simultaneously, namely, the segment of the dial h^1 that determines the ball to have been driven to center field, also to the section d^2 of the disk that designates the ball to have fallen on position No. 2 (shown dotted upon that position), and to the sub-section c^2 , containing the numerals 1 and 3, of which the latter has been chosen; therefore the batter will move three steps along the runway of the bases to position 3 where a counter representing such man is shown in broken line; but requiring one step more to reach first base.

The index numerals employed to carry the batter toward first base may be used to take the runner (previously batter No. 1) who was on first base at the beginning of this play on his way to second base, and is also shown (Fig. 1) on step No. 3, likewise one step from second base, in which positions the two runners in transit will be considered as remaining until a new spin, unless the fielders succeed in putting them out, whose actions will next be followed. Returning now to the ball-index j which is pointing to the section No. 5 of the disk which is found also to point to the sub-section of the disk containing the numeral 3, which, as we have seen, exactly carries the center fielder to the spot where the ball is shown to have been batted, and therefore counts as a catch by the fielder, who immediately decides to throw the ball to the second baseman, and the ball, as we have seen, must be thrown to position No. 5 according to the index. As the second baseman stands upon No. 4, one step removed the ball-index having a numeral 1, he too catches the ball without being in the present instance carried off his base, and therefore according to the rules of baseball the man "forced" to second base has been "put out." The second baseman then throws the ball to first baseman, again to position No. 5, the ball-index not having been changed, but as the first baseman stands upon position No. 1, which is either two or four steps from the ball, and having only the numerals 1 and 3 in the ball-index sub-section, he

therefore "muffs", that is, fails to catch the ball. The players both require new index numbers to complete the play, which will either carry the runner to his base or intercept and place him "out." The new spinning is made, let it be assumed, which results as shown in Fig. 3. The bat-index now points to a sub-section, in the disk which has the numerals 1 and 6, and as the former carries him to first base, he is declared "safe on first." Turning to the ball-index, it points to a subsection of the disk which contains the numerals 1 and 2; and as the first baseman is on position 1, and the ball is lying in position 5, two steps distant, his index number 2 enables him to recover the ball; there being nobody off base, the ball is consequently returned to the pitcher and the play is ended, with one man on first base and one man out.

The fourth batter next in order will take his place at the bat, it being borne in mind that the man a representing the third batter, which is shown in batting position on the board (Fig. 1) went to first base in the preceding play, therefore for illustrating the present play it will be considered that the fourth batter is occupying the place where the third is shown. The ball now being in the hands of the pitcher, the disk is spun again and comes to a stop in the position as shown in Fig. 3, it being immaterial that this identical setting has been used in connection with another play, which would be improbable in the actual operation of the apparatus, but is employed to avoid a needless multiplicity of views; in which setting the ball-index j points to section No. 3 of the disk, indicating that the ball has been thrown by the pitcher to position 3 at home-plate as shown in Fig. 4. As this ball has not been thrown over the home-plate, it must be counted a "called" ball, and is recorded by the pitcher piece moving to the portion of box e bearing the numeral 1.

It will be seen (Fig. 4) that the catcher stands at position 6, and, the ball having been thrown to number 3 as we have seen, which is three steps away, he fails to catch it, not having a numeral 3 in the sub-section of the ball-index. Taking the opportunity thus afforded by the catcher's "muff" to "steal" or earn a base the runner, player No. 1 moves one step from third base as the bat-index by the same setting points to a sub-section of the disk containing the numeral 1. The players having now exhausted their respective indexes, the disk and bat-index are spun a second time for the play, with the result as shown in Fig. 1, that the runner who was the first batter comes to the home-plate, the bat-index pointing to a sub-section of the disk having a numeral 3, which carries the runner evenly from the step on which he was taken on the former spin to

the home-plate, thereby completing a run home and ending the play. The inning now stands: One man out, one in, scoring a point for the side batting.

Starting in a manner similar to the preceding play, the fifth batter shown on the bench Fig. 1 comes to the bat and a ball is thrown as in the previous play; it will be assumed to have been put over the plate, and the batter strikes at the ball by spinning the bat-index, which is shown (Fig. 5) as pointing to a section of the dial b^1 indicating that the ball has been batted to first base to position No. 2 which is seen (Fig. 1) to be over the foul line k and therefore a foul ball, which, if counted as a strike, is recorded by moving the umpire piece a^3 to the square representing the numeral showing the total number of strikes for the play.

The ball is returned to the pitcher for another play, and it is again assumed that the pitcher has thrown the ball over the plate and that the batter has made a hit, which as shown in Fig. 3, is to the right field to position No. 6 but the right fielder is shown at position No. 6 (Fig. 1) and catches the ball on the fly, which, according to the rules of the game places a man out, making the score of two men out and one run. The next man in order comes to the bat in the manner described and I again assume that the disk has stopped in the position shown in Fig. 1. The ball having been again returned to the pitcher will then be thrown, that is, placed in position No. 5 on the board; the batter strikes at the ball by swinging the bat-index, which stops at the position shown in dotted lines, indicating that the ball has been batted to first baseman to position No. 4. It is also seen that the bat-index points to sub-section of disk containing the numerals 1 and 3, neither of which carries the man safely to the base, and he is placed upon step No. 3, which is the extent of his run. But, turning again to ball-index of the out-player it is seen that the sub-section of the disk contains the numeral 3, which exactly carried the first baseman from position 1 to position 4, recovering the ball which is upon position No. 4 and being exactly upon the base, under the rules of the game, puts the batter out, making three men out, or "side out."

The first half of the inning having closed, the men a^1 are then brought in from the fielders' stations and arranged upon the bench in batting order, while the men a are distributed among the fields upon whatever numbered stations may be chosen by the persons representing that side, and the second half of the inning is begun and will be completed according to the rules and in the manner that has been above described.

While the invention has been shown and described only in its most complete form, in

which substantially all the plays of a base-ball game are possible it will be understood that many features of the invention may be embodied in games of less complete form and the invention includes all uses of the novel features defined by the claims.

What I claim is:

1. In a base-ball gameboard, a ball-piece and men-pieces and single means for determining the moves of said pieces upon the board substantially in accordance with the movements of the ball and men upon a base-ball field.
2. A base-ball gameboard having a representation of a baseball field, a ball-piece and men-pieces, a dial, and single means for regulating the movements of the ball-piece and men-pieces upon the board in accordance with readings of said dial.
3. In a base-ball gameboard a diagram of a field, movable pieces representing players thereon, a ball-piece and means for simultaneously directing the movement of the said pieces about the board, substantially as described.
4. In a base-ball game-board, a diagram of the field, distinguishable movable pieces representing players of opposing teams thereon, a ball-piece and means for regulating the moves of said ball-piece upon the board including means for controlling simultaneously the moves of the men of said opposing teams in relation to each other and to said ball-piece.
5. A game apparatus comprising a board having a diagram representing a baseball field, pieces for locating thereon the ball, the runners and the out-fielders, in combination with single means for locating the ball on the board and for determining the position of players thereon as indicated, substantially as described.
6. In a baseball gameboard, a plurality of similar markings thereon designating plural positions for the ball and for individual fielders and basemen, substantially as described.
7. In a baseball gameboard, pluralities of similarly characterized markings thereon representing stands and runways for the ball and for all out players excepting the pitcher, substantially as described.
8. A baseball gameboard having a diagram comprising a diamond, a plurality of markings thereon designating base-plates and similarly arranged positions thereto, said markings also designating ball positions.
9. A baseball gameboard having a diagram comprising a diamond, a plurality of markings thereon designating base-plates and numerically indicated positions for the ball and for players relative thereto.
10. A baseball gameboard having a diagram comprising a diamond, representations

of base-plates, each provided with a plurality of designated positions for the ball and for players relative thereto, a portion only of said positions being in contact with the base-plates.

11. A baseball gameboard having a diagram comprising a diamond, representations of base-plates, each provided with a plurality of similarly designated positions for locating the ball and placing the men, a portion only of said portions being in contact with the base-plates.

12. In a baseball gameboard a representation of the pitcher's box divided into sections, said sections having the numerals 1, 2 and 3, substantially in the manner and for the purposes described.

13. In a baseball gameboard comprising a diagram, a representation of the umpire's stand and in combination therewith a graduated extension of said stand with the numerals 1 and 2, substantially as and for the purpose designated.

14. A gameboard having a baseball field comprising a diamond having representations of the pitcher's box, the catcher's stand and the home-plate, a series of designated positions at said home-plate in combination with plurality of lines extending from said box to said stand, said lines passing through the designated positions of said series, substantially in the manner and for the purposes described.

15. In a baseball gameboard having a representation of a diamond, the pitcher's box, the catcher's stand and the home-plate substantially as described, a series of numbered positions at said home-plate, a plurality of lines reaching from said box to said stand and passing through said numbered positions, a portion of said positions being at the sides of the said home-plate, substantially in the manner and for the purposes described.

16. In a baseball gameboard, similarly characterized stepped runways between bases, similarly characterized stepped runways at the bases and in the fields, and an indicating device adapted simultaneously to govern the progress of opposed players upon said runways, substantially as shown.

17. In a baseball gameboard having a ball-piece and men-pieces, stepped runways between bases, similar runways at the bases and in the fields, and an indicating device adapted to control the movements of the ball-piece and the progress of the men in relation to said runways.

18. In a baseball gameboard having a representation of a diamond and bases, stepped runways between said bases, representations of stands for the players, stepped runways at said players' stands, similarly arranged series of numerals designating the steps of the runways at said stands, and movable pieces representing the ball and the

players in combination with means consisting of an indicating device whereby said ball-piece may be located upon said runways and men-pieces moved in relation to 5 said ball-piece.

19. In a baseball gameboard having a diagram representing a field, a plurality of designated positions for the ball and for individual fielders in combination with an indicating device having designated sections substantially corresponding in number and arrangement to said fielders' positions.

20. In a baseball gameboard having a ball-piece and men-pieces and similarly 15 designated stepped runways, and an indicating device adapted to supply a choice of numbers whereby moves of said men-pieces upon said runways may be effected as desired.

21. In combination with a baseball gameboard, an indicating device having a rotatable disk divided into sections suitably designated, said sections being sub-divided into panels containing one or more numerals 25 substantially in the manner described.

22. In a baseball gameboard a board having a ball-piece and men-pieces, a diagram of said board having runways and ball positions in said runways, and an indicating device having two series of numbers and two 30 indexes whereby the movements of the ball and men pieces may be controlled substantially as described.

23. On a baseball gameboard having 35 marked thereon a diagram with bases and players' stands designated thereon and men-pieces representing opposing teams, stepped runways between bases and about the fielders' stands, a ball-piece and means consisting of an indicating device having two indexes, one of said indexes being adapted to 40 indicate batting results and to control the movements of in-players, and the other of said indexes being adapted to control the 45 plays of out-players, substantially as described.

24. A baseball gameboard having marked 50 thereon runways and ball positions in combination with an indicating device having a dial divided into panels containing imprints of players' titles and the word "strike," and a rotating disk concentric to and within said

dial having two sets of numbers, substantially as described.

25. A baseball gameboard having marked 55 thereon runways and ball positions substantially as described in combination with an indicating device having a dial containing panels with titles of players and the word "strike," a disk rotatable with relation to 60 said dial and having two sets of numbers; a fixed index and a revoluble index each adapted to select from said sets of numbers, and one of said indexes adapted to select also one of said panels. 65

26. In a baseball gameboard a diagram of 70 a field with positions for the individual players thereon in combination with an indicating device adapted to indicate batting results, comprising a dial having panels 75 designating fielding positions and panels containing the word "strike."

27. In a baseball gameboard a ball-piece and a plurality of pieces to represent players, a diagram of a baseball field with pluralities of positions and runways for individual players substantially as described, in combination with an indicating device having two sets of numbers, one set thereof adapted to control the position of the ball 80 on said field the other set of numbers being arranged singly and in groups said groups adapted to supply an option of numbers to the player for controlling the movements of the men pieces. 85

28. A baseball gameboard having therein 90 a diagram of a field with representations of players' stands, having graduated runways with ball positions in said runways, in combination with an indicating device comprising a dial upon which fielding positions are indicated, a rotatable member upon which numerals are arranged, a revoluble index adapted to point to said fielding positions and to said numerals and a fixed pointer 95 adapted to select numerals upon said rotatable member.

In testimony whereof, I have hereunto set my hand, in the presence of two subscribing witnesses.

WALTER J. ENNISON.
